(**) Term: **15 Years**

CLAIM

(21) Appl. No.: **29/539,136**

The ornamental design for a lens for television camera, as shown and described.

(22) Filed: **Sep. 11, 2015**

DESCRIPTION

(30) **Foreign Application Priority Data**

Mar. 13, 2015 (JP) 2015-005492
Mar. 13, 2015 (JP) 2015-005493
Mar. 13, 2015 (JP) 2015-005494

(51) **LOC (10) Cl.** **16-05**

FIG. 1 is a top, front and left side perspective view of a lens for television camera showing a first embodiment of my new design;

(52) **U.S. Cl.** **USPC D16/219**

FIG. 2 is a bottom, front and left side perspective view thereof;

(58) **Field of Classification Search**

FIG. 3 is a front elevational view thereof;

USPC D16/134, 136, 202, 219, 243; 348/373,
348/374, 375, 376; 396/432, 535, 544;

FIG. 4 is a rear elevational view thereof;

378/98.2

FIG. 5 is a top plan view thereof;

CPC H04N 5/772; H04N 7/0105; H04N 5/05;
H04N 5/372; G11B 20/10527; G11B
2020/10592

FIG. 6 is a bottom plan view thereof;

See application file for complete search history.

FIG. 7 is a left side elevational view thereof;

(56) **References Cited**

FIG. 8 is a right side elevational view thereof;

U.S. PATENT DOCUMENTS

FIG. 9 is a right side elevational view thereof in a manner of use;

D416,271 S * 11/1999 Ikenaga D16/202
D469,792 S * 2/2003 Kawashima D16/134
